United States Patent Office

Des. 204,381
Patented Apr. 12, 1966

204,381

DENTAL ARTICULATOR

Peter P. Orofino, Flushing, N.Y., assignor to Allen Dynamics, Inc., New York, N.Y., a corporation of New York

Filed June 14, 1965, Ser. No. 85,721

Term of patent 14 years

(Cl. D24—1)

FIG. 2

FIG. 3

FIG. 4

FIG. 1

FIGURE 1 is a perspective view of a dental articulator, showing my new design;

FIGURE 2 is a side view thereof;

FIGURE 3 is an end view thereof; and

FIGURE 4 is a top plan view thereof.

I claim:

The ornamental design for a dental articulator, substantially as shown.
